UNITED STATES PATENT OFFICE.

JOHN THOMAS WILLIAMS, OF LOS ANGELES, CALIFORNIA.

STILE-HORNING MACHINE.

Application filed January 3, 1923. Serial No. 610,509.

To all whom it may concern:

Be it known that I, JOHN T. WILLIAMS, a citizen of the United States, and a resident of Los Angeles, in the county of Los Angeles and State of California, have invented a new and Improved Stile-Horning Machine, of which the following is a full, clear, and exact description.

This invention relates to woodworking machinery, and more particularly to such class of machinery which includes a rotary cutter toward which the work may be advanced for shaping.

As the invention is preferably carried out, the same provides a stile horning machine, that is, a machine for horning or giving a reversely curved shaping to an end of a window stile; and, as a horning machine for the purpose just indicated may most practically be embodied, pursuant to the invention, the same may be constructed as an auxiliary apparatus for attachment to the main frame of a sash-sticker, shaper or spindle machine, to save an extra man's time, one machine, and a handling of stiles twice.

As thus preferably embodied, the prime object of the invention is to provide, in combination with the rotary cutter, a work-support including a movable carriage for directly holding the stile and adapted easily and rapidly to be given a plurality of characteristically dissimilar movements to bring the stile end to be horned into the field of operation of the cutter in such manner as to cause the single cutter to horn the stile end to shape the same to a surface presenting a portion concavely curved and convexly curved.

Another object of the invention is to provide work holding and guiding means of the kind last indicated and having associated therewith sequentially operable carriage shifting means, whereby one of such means may conveniently be pedal-operated and the other may conveniently be hand-operated, to facilitate convenience, minimize fatigue of the attendant, and make rapid production possible and highly economical.

A further object is to provide in a machine as described, a mounting for the carriage such that the same is limited to a movement of translation, preferably in a straight line, toward and away from the cutter, and to a movement of rotation to advance the work toward and away from the cutter; and, in connection with such car-

riage mounting, to design the same so that at the end of one of such movements of the carriage, the carriage is then and then only adjusted for its other movement.

Still a further object is to provide a structure of the kind above specified in which a single spring means or equivalent may be employed for normally holding the carriage away from the cutter, and yet a means automatically functioning, as soon as a movement of translation of the carriage toward the cutter is completed, to urge the carriage toward its movement of rotation.

A further object of the invention is to provide, in a machine of the above nature, the pedal and handle aforesaid so arranged that the handle need be employed, after completion of the second characteristic movement of the carriage, only to move the carriage back to the position it occupied at the completion of its first characteristic movement.

Still another object of the invention is to provide a guard for the cutter, but adjustable relative thereto, and automatically adjusted as the result of the various carriage movements for maximum protective action at all times during the complete stile horning operation.

Other objects and aims of the invention, more or less broad than those stated above, together with the advantages inherent, will be in part obvious, and in part specifically referred to in the course of the following description of the elements, combinations, arrangements of parts, and applications of principles constituting the invention; and the scope of protection contemplated will appear from the claims.

In the accompanying drawings, which show, by way of illustration merely, and as one example of how the invention may be carried out, an embodiment thereof adapted to be attached to a sash-sticker,

Fig. 1 is a top plan view, partially broken away and partially in section,—the stile not yet being advanced toward the rotary cutter;

Fig. 2 is a view similar to Fig. 1, but showing certain of the parts redispersed and the stile partially horned;

Fig. 3 is a view similar to Figs. 1 and 2, but showing certain of the parts further redispersed and the horning operation practically completed;

Fig. 4 is a vertical section, taken on line 4—4 of Fig. 2;

Fig. 5 is a vertical section, taken on line 5—5 of Fig. 2;

Fig. 6 is a top plan view of one of the two slot-carrying plates; and

Fig. 7 is a similar view of the other of said plates.

Like characters of reference refer to like parts throughout the several views of the drawings.

10 The main support or bed is shown at 8; which support or bed may desirably form a part of a familiar sticker, shaper, spindle machine or the like, so as preferably to employ the new apparatus as an attachment for 15 a sash-sticker or similar machine and in such position that the cutting device of the new apparatus may horn each window stile as it goes through the sticker.

Despite the apparent first-glance complexity of the drawings, the new apparatus, as here illustratively embodied, comprises but very few parts.

These parts include an upright milling cutter 9, fixed on a vertical shaft 10 and 25 adapted to be rotated by any suitable power means (not shown) to constitute a cutting device for horning the end of a stile 10 advanced toward the cutter; a cutter-guard 11 loosely taking the shaft 9^a above and 30 below the cutter as indicated best at 11^a in Fig. 4, and a pair of upper and lower horizontal plates 12 and 13. The lower plate 13 is fixed to bed 8 in any suitable manner. The upper plate 12, carrying rigidly a stile- 35 holder or carriage 14 (so that really this plate 12 and the carriage are one structure constituting the complete carriage), is edge- 40 wisely movable relative to the lower plate 13, by means of post and slot connections hereinafter described more in detail, first, to have a movement of translation along a straight line, to perform the first part of the stile-horning cut, and, finally, to have a movement of rotation about a fixed point, 45 to perform the second part of the stile-horning cut.

The only other elements of the apparatus are coacting slots and posts, as just mentioned, certain of which are carried by plate 12, and certain of which are carried by plate 13, for guiding the upper plate 12 to have a translational movement and an ensuing rotational movement in its own plane while sliding over lower plate 13; a pedal 15 (Fig. 4) for giving the said upper plate its movement of translation, to advance the stile end toward the cutter; a retractile coil spring 16 (Fig. 4) normally urging the sliding plate 12 to hold the stile end away from said cutter; a handle 17 (Fig. 1) forming a rigid prolongation of carriage 14 fixed on top of upper sliding plate 12, for giving said upper plate its movement of rotation; and an operative connection between cutter- 60 guard 11 and said upper plate, such con-

nexion including (Figs. 1 and 4) a slotted arm 18 fixedly offset from the bottom of the guard and having its slot engaged by the lower portion of the shank of a depending threaded rod 19 the upper end of which is clamped by nuts as illustrated to a reduced extension 12^a of upper sliding plate 12, thereby automatically and continuously to vary the setting of the cutter-guard for maximum protective action at all times as 75 horning of the stile progresses.

Referring now particularly to the coacting slots and posts certain of which are carried as aforesaid by each of the plates 12 and 13, compare Figs. 6 and 7 with Fig. 1. The lower fixed plate 13 of Fig. 7 has cut therethrough a pear-shaped slot 20 and an L-shaped slot 21; and upper sliding plate 12 has cut therethrough a straight slot 22 and an L-shaped slot 23. Each of the two slots in each of the plates takes its own separate post fixedly carried by the other plate. Thus, referring for a moment also to Fig. 4, posts 20^a and 21^a, respectively taking the slots 20 and 21 in the lower plate 13, are securely mounted to depend from the upper plate 12; while, referring for a moment also to Fig. 5, posts 22^a and 23^a respectively taking the slots 22 and 23 in the upper plate 12, are securely mounted on 90 lower plate 13 to extend above the same.

The stile-holding carriage 14 being screwed fixedly atop the upper sliding-plate 12, as by means of the three screws marked 24 in Fig. 3, all the slots and posts except slot 21 and post 21^a are hidden in Figs. 1, 2 and 3.

Referring next to the function of the spring 16 of Fig. 4, which spring, it will be noted, is stretched between a hook 24 at the lower end of threaded rod 19 and a hook 25 carried at the lower end of a swiveled stud 26 set in a suitably drilled hole in the bed 8 of the main machine, it will be seen from a reference to Fig. 1, that such spring normally urges the parts to maintain the relative positions there shown and impositively locks said parts in these positions by applying pressures away from the cutter to the pins 20^a and 21^a carried by the upper sliding plate; and it will further be seen by a reference to Figs. 2 and 3, that the same spring, as soon as the parts are moved from the positions of Fig. 1 to those of Fig. 2, immediately urges the parts toward the positions of Fig. 3, that is, applies pressures away from and to the left of the cutter, to the same pins 20^a and 21^a carried by the upper sliding plate.

Referring next to the operative connection between pedal 15, which pedal is pivotally mounted as indicated at 27 in Fig. 4, it will be seen that the rear end of the pedal is connected by a link 28 to a lever 29 pivoted at 30, the upper end of which lever is connected by a cable 31 to a hook 32 at the lower 130

end of a rod 33 forming a prolongation of post 21^a.

The just-mentioned pivotal mounting for lever 29 is afforded by a depending bracket 34 carried by a member or housing 35 forming a part of the new apparatus and suitably attached to bed 8 of the sash-sticker. This structure 35 carries suitable journalling supports (not shown) for shaft 9^a of cutter 9.

10

Operation:

With the parts arranged as shown in Fig. 1, and with the cutter 9 of course rotating in a clockwise direction, a stile 10, having been 15 slid all the way into carriage 14, is advanced at the angle indicated toward cutter 9, as the result of a straight-line movement of upper sliding plate 12 toward the cutter; this movement of the upper sliding plate 20 following from a depression of pedal 15, against the tension of spring 16, and a consequent travel of pins 20^a and 21^a in their slots toward the cutter and a simultaneous travel of slots 22 and 23 of upper sliding 25 plate 12 past their posts. At the conclusion of such travel of upper sliding plate 12, the cutter 9 has completed the concave horning cut marked 36 in Fig. 2 and the posts and slots are disposed as shown in Fig. 2. Immediately upon this happening, pressure on the pedal 15 is released, whereupon spring 16 exerts a pull upon upper sliding plate 12 to give the same a tendency to swing about post 22^a fixed on lower fixed plate 13, as a 30 result of which, and during the performing of the convex horning cut 37 of Fig. 3, the upper sliding plate 12 is rotated to the position shown in said Fig. 3. During such rotation the curved limb of slot 23 in upper 35 sliding plate 12 travels past fixed post 23^a, and simultaneously posts 20^a and 21^a of the upper sliding plate travel through slots 20 and 21 of the fixed plate 13. These slots and posts are thus arranged as shown in 40 Fig. 3 when the horning of the stile end is practically completed. In this connection it will be seen that the curved limbs of slots 21 and 23 and the long curved side of slot 20 are all arcuate on radii of different lengths 45 but with each radius terminating at the center of post 22^a when the parts are moved from the positions of Fig. 1 to those of Fig. 2. As soon as the stile end is completely 50 horned as just described, the attendant 55 grasps the handle 17 and pushes the same to redispose the parts from the positions of Fig. 3 to those of Fig. 2; whereupon spring 16 again automatically functions, this time to throw the parts back to the positions of 60 Fig. 1. During the operations above described in order, it will be seen that the pin and slot connection afforded by the parts 18 and 19 between sliding plate 12 and cutter guard 11 automatically functions to shift 65 the guard relative to the cutter as required

to maintain the guard always out of contact with the adjacent portions of the stile being horned and yet always to provide the maximum protection possible at the field of cutting.

Inasmuch as many changes could be made in the above construction, and many apparently widely different embodiments of my invention could be made without departing from the scope thereof, it is intended that all matter contained in the above description or shown in the accompanying drawings shall be interpreted as illustrative and not in a limiting sense.

It will also be understood that the language used in the following claims is intended to cover all the generic and specific features of the invention herein described and all statements of the invention which, as a matter of language, might be said to fall therebetween.

I claim:

1. In a wood-working apparatus, the combination of cutting means including a rotary cutter, a fixed support, a work-holding carriage movable on said support, and means for holding the carriage to a rotational movement while precluding the carriage from having a translational movement, and means for thereupon holding the carriage to a translational movement while precluding the carriage from having a rotational movement.

2. The apparatus defined in claim 1, wherein the two means last mentioned include solely a plurality of directly co-acting elements certain of which are fixed relative to the support and all others of which are fixed relative to the carriage.

3. The apparatus defined in claim 1, wherein the two means last mentioned include solely a plurality of post and slot connections between carriage and support.

4. The apparatus defined in claim 1, wherein said support and carriage each includes a plate and wherein the two means last mentioned include a substantially L-shaped slot in one of the plates, a post on the other plate engaging said slot, a straight slot on one of the plates, and a post on the plate other than the one carrying the straight slot, the post last mentioned engaging said straight slot.

5. In a woodworking apparatus, the combination of cutting means including a rotary cutter, a fixed support, a work-holding carriage movable on said support, and guiding means for the carriage partially carried thereby and partially carried by the support for limiting the carriage to a movement of translation toward and away from the cutter and to a movement of rotation toward and away from the cutter, said support being a plate having its upper surface in a plane substantially perpendicular to the axis of

70

- rotation of the cutter, and said carriage at its bottom including a plate having its lower surface in face-to-face contact with the upper surface of the first-mentioned plate, said 5 guiding means including a substantially L-shaped slot in each plate and a post on each plate, each post of each plate extending into the slot in the other plate. 50
6. In a woodworking apparatus, the combination of cutting means including a rotary cutter, a fixed support, a work-holding carriage movable on said support, and guiding means for the carriage partially carried thereby and partially carried by the support 55 for limiting the carriage to a movement of translation toward and away from the cutter and to a movement of rotation toward and away from the cutter, said guiding means including a plurality of pin and slot connections between carriage and support, said connections including an L-shaped slot, one limb of the L being straight and the other limb being curved. 60
7. In a woodworking apparatus, the combination of cutting means including a rotary cutter, a fixed support, a work-holding carriage movable on said support, and guiding means for the carriage partially carried thereby and partially carried by the support 65 for limiting the carriage to a movement of translation toward and away from the cutter and to a movement of rotation toward and away from the cutter, a single spring means being provided for normally holding the carriage at a limit of its movement of translation and with the work retracted from the cutter and for automatically urging the cutter to a movement of rotation when the carriage is moved to the other limit of its movement of translation. 70
8. In a woodworking apparatus, the combination of cutting means including a rotary cutter, a fixed support, a work-holding carriage movable on said support, and guiding means for the carriage partially carried thereby and partially carried by the support 75 for limiting the carriage to a movement of translation toward and away from the cutter and to a movement of rotation toward and away from the cutter, a single spring means being provided for normally holding the carriage at a limit of its movement of translation and with the work retracted from the cutter and for automatically urging the cutter to a movement of rotation when the carriage is moved to the other limit of its movement of translation, there being also provided means operable at will to move the carriage against said spring toward the cutter while giving the carriage a movement of 80 translation. 85
9. In a woodworking apparatus, the combination of cutting means including a rotary cutter, a fixed support, a work-holding carriage movable on said support, and guiding means for the carriage partially carried thereby and partially carried by the support 90 for limiting the carriage to a movement of translation toward and away from the cutter and to a movement of rotation toward and away from the cutter, a single spring means being provided for normally holding the carriage at a limit of its movement of translation and with the work retracted from the cutter and for automatically urging the cutter to a movement of rotation when the carriage is moved to the other limit of its movement of translation. 95

JOHN THOMAS WILLIAMS.
